UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

REINFORCING MEANS FOR METALLIC PLATES.

Application filed August 27, 1926. Serial No. 131,940.

Reference is had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

My invention relates to means of reenforcing a metallic plate by forming integral corrugations, embossments or ribs therein and resides in the particular and peculiar configuration and relation of the corrugations to obtain certain desired results.

15 An object of the invention is to form and arrange a plurality of corrugations in a metallic plate so as to obtain a desired proportion between strength, rigidity and resiliency.

Another object is to obtain this result with 20 the least amount of raw material and to provide a finished article of the least possible weight consistent with strength requirements.

Another object is to obtain the desired 25 strength, rigidity and resiliency by forming a metallic plate with integral corrugations or ribs which increase in width toward their opposite ends and other alternate corrugations or ribs which project in the opposite 30 direction therefrom and which decrease in width toward their opposite ends, the last mentioned corrugations being formed with integral ribs which terminate therewithin to provide a certain amount of resiliency to enable the plate to deflect and return to its normal 35 position without appreciable permanent distortion.

Another object is to form a metallic plate with a plurality of corrugations which are 40 all of the same depth for the major portion of their length and are equal in depth to each other so as to form a substantially flush surface on one side of the plate (or railway car structure) and to also form the plate with 45 oppositely projecting corrugations positioned alternately therebetween which are deepest adjacent their middle and decrease in depth toward their opposite ends. Another object is to merge the adjacent portions 50 of the oppositely projecting corrugations into each other so as to provide, in effect, a plurality of corrugations having a depth equal to the total depth of the oppositely projecting corrugations.

55 Another object is to provide such a cor-

rugated metallic plate which can be formed by pressing it (when heated, if necessary) between dies which move toward each other in one direction only.

The construction may be used wherever a 60 strong, resilient panel is desired, but is especially adaptable for railway car structures, such as end walls, side or end doors, hopper doors, floors, roofs, etc.

It is well known that the end walls of railway cars are more likely to be broken or otherwise injured than the side walls. This is due to the inertia thrusts and pressures caused by the shifting of the cargoes when the train starts or stops. These thrusts may 70 be local, tending to distort the end in some particular spot, as, for example, when a piece of piping or lumber shifts lengthwise imparting a blow against the end wall of the car; or there may be a general tendency to break 75 out of the wall as a whole or tear it away from the framing. For the purpose, therefore, of greater strength and durability, car ends have been constructed of metal plates 80 corrugated or formed with ribs to impart the desired strength, rigidity and resiliency. My construction is especially adaptable to end walls for railway cars (of any type) because it has the strength to resist the continuous pounding of the shifting loads thereon 85 and has the resiliency necessary to absorb these numerous shocks without distortion. Distortion of an end wall might bend the 90 brake mast, thereby causing interference with the operation of the hand brake mechanism. Furthermore, such distortion might reduce the end ladder clearance beyond that prescribed by the Interstate Commerce Commission. When made of several plates secured 95 together the end wall can be made stronger where greater strength is required. A wooden inside lining is required in a railway house car for blocking the lading to and for compliance with the requirements of the Bureau of Explosives of the American 100 Railway Association. Such a wooden lining can be easily applied to my construction.

In the drawings:

Fig. 1 shows a typical application of my device to a railway box car.

Fig. 6 is an enlarged detail of a plate reenforced by my arrangement of corrugations.

Fig. 7 is a section on line 7—7 of Fig. 6.

Fig. 8 is a section on line 8—8 of Fig. 6.

Fig. 9 is a section on line 9—9 of Fig. 6.

Fig. 10 is a section on line 10—10 of Fig. 6.

Fig. 11 is a side view of Fig. 6.

Fig. 12 is a section on line 12—12 of Fig. 6.

The plate is formed of integral corrugations or ribs 2—3 projecting alternately in opposite directions and preferably having their sides 4—5 merging into the adjacent corrugations so as to provide, in effect, a plurality of parallel corrugations having a depth equal to the total depth of the oppositely projecting corrugations. Adjacent their ends the corrugations are spaced apart distances equal to their widths so that the neutral axis of the corrugated section is midway between the bounding planes of the corrugated structure. The apices 7—8 of the corrugations are preferably arched so as to transmit any load imposed upon them to the opposite side walls 4—5 of the corrugations. This arched formation has the further advantage of reducing the stretch of the metal in pressing the corrugations in the plate. I have used the terms "embossments" and "depressions" in the specification and claims to avoid confusion and differentiate between the corrugations projecting one way from the original plane 9 of the plate and those projecting in the opposite direction thereto, but otherwise I contemplate no difference in the meaning of the terms.

In the construction illustrated the embossments 2 have a constant width and depth for a space 6 equi-distant on each side of the middle of the plate and then increase in width (and preferably also in depth) until they merge into the original plane 9 of the plate at 10. (See Fig. 9.)

The depressions 3 are positioned alternately between the embossments 2 and preferably have a constant width and depth for a space 6 equi-distant on each side of the middle of the plate and then preferably maintain a constant depth but decrease in width toward their opposite ends proportionately to the increase in width of the embossments so that the adjacent sides 4—5 of the embossments and depressions are parallel, and in the preferred form, these sides merge into each other.

The depressions 3 have integral ribs 11 formed in them which project in opposite directions therefrom and are preferably equal in depth thereto adjacent the middle of the depression and preferably equi-distant on each side of their medial line. These ribs preferably terminate within the depression. The embossments and depressions are equal in width adjacent their ends. The embossments, ribs and the portions of the depression on opposite sides of the ribs are all the

same width (and preferably of constant width) adjacent the middle and preferably equi-distant on opposite sides of their medial line. The depressions are provided with terminal portions which merge into the original plane of the plate.

The various contours of the corrugations are preferably such that the center lines of the metal at any cross section of the corrugated plate normal to the corrugations are equal. Furthermore, the metal is so disposed as to provide the required strength at any cross section thereof to sustain an equally distributed load.

Fig. 12 shows the embossments 2, depressions 3 and the ribs 11 formed in the depressions.

The embossments and depressions may be of equal depth or one group may be deeper than the other group to suit conditions. In the form illustrated the embossments are shallower than the depressions.

By thus forming a metallic plate I provide a plurality of corrugations or beams which cooperate to form a very strong structure adjacent the sides of the plate capable of absorbing considerable stress without much deflection and which also form a resilient structure adjacent the middle of the corrugations so that when the plate deflects under extreme load it rebounds or returns to its normal position without appreciable permanent distortion.

The drawings show the device applied to a railway box car having an end sill 30, end plate 31 and oppositely disposed corner post 32. The sides of the plates forming the panel are provided with flanges 33 which are secured to the corner post. The inwardly projecting corrugations (either embossments or depressions) are of constant depth for the major portion of their length so as to provide a substantial flush surface on the inside of the car to support the lining boards 34 which bear against them. Nailing strips 35 are provided which are bolted or otherwise secured to the corrugated plate to which the lining boards are nailed. The end plate 31 is reenforced by the top corrugation 36 which is positioned adjacent thereto.

The end wall structure comprises one or more corrugated metallic plates secured together to form a panel. The corrugations may be positioned horizontally, vertically or obliquely and the connecting seams between the corrugated plates may be positioned horizontally, vertically or obliquely, as desired. Experience has shown that the upper portion of the end wall of a railway car is not subjected to as severe stresses as the lower portion, therefore, I prefer to make the upper plates of thinner material than the lower plates, thereby reducing the weight of the car as well as its cost. I have illustrated a device applied to a box car. However, it is

applicable to any type of railway equipment, such as automobile cars, gondola cars, stock cars, or the like.

This structure has certain advantages not contained in the structures disclosed and claimed in my co-pending applications Serial No. 595,632, now Patent No. 1,674,137, dated June 19, 1928, filed October 19, 1922; Serial No. 595,634, filed October 19, 1922, and Serial No. 120,732, filed July 6, 1926.

I claim:

1. In a railway car construction, a metallic plate formed with a plurality of embossments increasing in width toward their ends, and a plurality of depressions decreasing in width toward their ends, said embossments and depressions projecting in opposite directions from the original plane of the plate, and ribs formed in said depressions which terminate therewithin.

2. In a railway car construction, a metallic plate formed with a plurality of embossments increasing in width toward their ends, and a plurality of depressions decreasing in width toward their ends, said embossments and depressions projecting in opposite directions from the original plane of the plate, and ribs formed in said depressions which terminate therewithin, said embossments and depressions being the same width adjacent their ends.

3. In a railway car construction, a metallic plate formed with a plurality of embossments increasing in width toward their ends, and a plurality of depressions decreasing in width toward their ends, said embossments and depressions projecting in opposite directions from the original plane of the plate, and ribs formed in said depressions which terminate therewithin, said embossments, ribs and portions of the depressions on opposite sides of the ribs all being the same width adjacent their middle.

4. In a railway car construction, a metallic plate formed with a plurality of embossments increasing in width toward their ends, and a plurality of depressions decreasing in width toward their ends, said embossments and depressions projecting in opposite directions from the original plane of the plate, and ribs formed in said depressions which terminate therewithin, said embossments, ribs and portions of the depressions on opposite sides of the ribs all being the same width and of constant width equidistant on opposite sides of their medial line.

5. In a railway car construction, a metallic plate formed with a plurality of embossments increasing in width toward their ends, and a plurality of depressions positioned alternately therewith decreasing in width toward their ends, said embossments and depressions projecting in opposite directions from the original plane of the plate, and ribs formed in said depressions which terminate therewithin

with the sides of the embossments merging into the sides of the depressions.

6. In a railway car construction, a metallic plate formed with a plurality of embossments increasing in width toward their ends, and a plurality of depressions positioned alternately therewith decreasing in width toward their ends, said embossments and depressions projecting in opposite directions from the original plane of the plate, and ribs formed in said depressions which terminate therewithin with the sides of the embossments merging into the sides of the depressions for the entire length of these elements.

7. In a railway car construction, a metallic plate formed with a plurality of embossments increasing in width and decreasing in depth toward their ends, and a plurality of depressions decreasing in width toward their ends, said embossments and depressions projecting in opposite directions from the original plane of the plate, and ribs formed in said depressions which terminate therewithin.

8. In a railway car construction, a metallic plate formed with a plurality of embossments increasing in width toward their ends, and a plurality of depressions of constant depth the major portion of their length and decreasing in width toward their ends, said embossments and depressions projecting in opposite directions from the original plane of the plate, and ribs formed in said depressions which terminate therewithin.

9. In a railway car construction, a metallic plate formed with a plurality of embossments increasing in width and decreasing in depth toward their ends, and a plurality of depressions positioned alternately therewith of constant depth the major portion of their length and decreasing in width toward their ends, said embossments and depressions projecting in opposite directions from the original plane of the plate, and ribs formed in said depressions which terminate therewithin.

10. In a railway car construction, a metallic plate formed with a plurality of embossments increasing in width toward their ends, and a plurality of depressions decreasing in width toward their ends, said embossments and depressions projecting in opposite directions from the original plane of the plate, and ribs formed in said depressions which terminate therewithin, said embossments, ribs and portions of the depressions on opposite sides of the ribs all being the same width adjacent their middle with the sides of the embossments merging into the sides of the depressions for the entire length of these elements, said embossments and depressions being the same width adjacent their ends.

11. In a railway car construction, a metallic plate formed with a plurality of embossments increasing in width toward their ends, and a plurality of depressions decreasing in

- width toward their ends, said embossments and depressions projecting in opposite directions from the original plane of the plate, and ribs formed in said depressions which are 5 equal in depth thereto adjacent their middle and terminate therewithin.
12. A metallic plate formed with a plurality of alternately disposed oppositely projecting corrugations, some of which have 10 other corrugations formed therewithin, so as to provide a relatively rigid structure adjacent the ends of the corrugations, and a relatively resilient structure adjacent the middle of the corrugations.
13. In a railway car structure, a metallic plate formed with a plurality of embossments which decrease in depth toward their opposite ends and terminate within the plate adjacent the opposite edges of the structure, 15 said plate also formed with a plurality of depressions of constant depth the major portion of their length and terminating within the plate adjacent the opposite edges of the structure, said embossments and depressions projecting in opposite directions from the original plane of the plate and ribs formed in said depressions which terminate therewithin.
14. In a railway car structure, a metallic plate formed with a plurality of embossments which decrease in depth toward their opposite ends and terminate within the plate adjacent the opposite edges of the structure, 20 said plate also formed with a plurality of depressions positioned alternately therebetween of constant depth the major portion of their length and terminating within the plate adjacent the opposite edges of the structure, said embossments and depressions 25 projecting in opposite directions from the original plane of the plate and ribs formed in said depressions which terminate therewithin.
15. In a railway car structure, a metallic plate formed with a plurality of embossments which decrease in depth toward their opposite ends and terminate within the plate adjacent the opposite edges of the structure, 30 said plate also formed with a plurality of depressions positioned alternately therebetween of constant depth the major portion of their length and terminating within the plate adjacent the opposite edges of the structure, said embossments and depressions 35 projecting in opposite directions from the original plane of the plate, ribs formed in said depressions which terminate therewithin, and a lining bearing against said depressions and secured to the plate.
16. In a railway car structure, a metallic plate formed with a plurality of embossments of constant depth for a short distance adjacent their middle which decrease in depth 40 toward their opposite ends and terminate within the plate adjacent the opposite edges 45

of the structure, said plate also formed with a plurality of depressions of constant depth the major portion of their length and terminating within the plate adjacent the opposite edges of the structure, said embossments and depressions projecting in opposite directions from the original plane of the plate, and ribs formed in said depressions which terminate therewithin. 70

17. In a railway car structure, a metallic plate formed with a plurality of corrugations projecting in opposite directions from the original plane of the plate, some of which have their middle portions divided so as to provide a relatively rigid structure adjacent the opposite ends of the corrugations and a relatively resilient structure adjacent the middle of the corrugations. 75 80

18. In a railway car structure, a metallic plate formed with a plurality of corrugations projecting in opposite directions from the original plane of the plate, some of which have their middle portions divided so as to provide a relatively rigid structure adjacent the opposite ends of the corrugations which 90 gradually becomes a relatively resilient structure adjacent the middle of the corrugations. 95

19. In a railway car structure, a metallic plate formed with a plurality of corrugations projecting in opposite directions from the original plane of the plate which are relatively deep adjacent their end portions, some of which have their middle portions divided to form a greater number of corrugations adjacent their middle portions so as to provide a relatively rigid structure adjacent the ends of the corrugations and a relatively resilient structure adjacent the middle of the corrugations. 100 105

20. In a railway car structure, a metallic plate formed with a plurality of corrugations projecting in opposite directions from the original plane of the plate which are relatively deep adjacent their end portions, some of which have their middle portions divided to form a greater number of corrugations adjacent the middle portions so as to provide a relatively rigid structure adjacent the ends of the corrugations which gradually becomes 115 a relatively resilient structure adjacent the middle of the corrugations. 110

21. In a railway car structure, a metallic plate formed with a plurality of corrugations projecting in opposite directions from the original plane of the plate which are relatively deep and relatively wide adjacent their end portions, some of which have their middle portions divided to form a greater number of relatively shallow and relatively narrow corrugations adjacent their middle portions so as to provide a relatively rigid structure adjacent the ends of the corrugations and a relatively resilient structure adjacent the middle of the corrugations. 120 125 130

22. In a railway car structure, a metallic plate formed with a plurality of corrugations projecting in opposite directions from the original plane of the plate which are relatively deep and relatively wide adjacent their end portions, some of which have their middle portions divided to form a greater number of relatively shallow and relatively

narrow corrugations adjacent their middle portions so as to provide a relatively rigid structure adjacent the ends of the corrugations and which gradually becomes a relatively resilient structure adjacent the middle of the corrugations. 10

ARTHUR E. SMALL.
